BRUSH BRISTLE FEED CONTROL

Si I. Spiegel, Mount Vernon, N.Y., assignor to American Brush Machinery Co., Inc., Mount Vernon, N.Y., a corporation of New York

Filed Nov. 25, 1960, Ser. No. 71,796

14 Claims. (Cl. 300—2)

This invention is directed to a novel feed control for brush bristles in an automatic brush making machine such as shown in Patent 2,742,327.

In such machine, during each brush forming cycle or routine, bristles are picked in clusters from a supply store and transferred to insert position between a pair of binding wires being fed past insert position by a traveling chuck. When a desired length of wires has been fed during a wire feeding period in the cycle, the chuck is rotated to twist the wires together, locking the inserted bristle clusters into the twisted wire loops. The wires are then cut behind the twisted portion and the chuck opened to drop the work into a receiving space. Bristle insertion is stopped before the end of the wire feeding period and is not restarted until the next wire feeding period in the next brush forming cycle. By stopping insertion before the end of the wire feeding period, a terminal portion of the fed length of wires is left bare of bristles. When the wires are cut after the twisting operation, a substantial part of the bare portion of the wires remains as the leading end of the wires to be grasped by the chuck for the next wire feeding stroke.

Heretofore, the insertion and skipping of bristles between the brushing wires have been controlled by driving the bristle picking and bristle inserting means through clutch means engaged to drive the picking and inserting means for transferring bristles from the store to the wires and disengaged to interrupt drive of the picking and inserting means and cause skipping of bristle insertion. The intermittent clutching and declutching of the bristle picking and inserting mechanisms produces momentum and inertia effects which strain the mechanism and interfere with smoothness of operation. Further, the clutching and declutching actions and their side effects lessen the effective and permissible speed of operation of the bristle transferring means and, therefore, of the machine as a whole.

An object of the invention is to control the transfer of bristles from a supple store to the binding wires without clutching and declutching of the bristle picking and inserting means. The invention functions to control transfer and interruption of transfer of bristles to the binding wires while permitting the bristle picking and inserting means to continue running uninterrupted.

The bristle transferring means between the supply store and the binding wires may comprise, as in said patent, a picker wheel to collect bristle clusters from the store and a pin wheel to take the clusters from the picker wheel and bring them to insert position between the binding wires. Alternatively, the bristle transferring means may be a bristle picking wheel which collects the bristles in clusters from the store and brings them directly to insert position between the binding wires. In either case, the invention provides bristle feed control means for opening and closing the store for the required times during the brush forming cycles. Operation of the feed control means can be effected through a solenoid or through

2

a fluid actuator or mechanically as through cam means controlled by a cyclically functioning element of the machine.

Other objects of the invention reside in any other novel feature or combination of features present in the disclosed apparatus, as will appear from the following portions of the specification and from the drawings, wherein:

FIG. 1 is a perspective view of the section of an automatic brush making machine to which the invention is applied;

FIG. 2 is a fragmentary right side view of illustrative actuating means for the bristle feed controller involved in the invention;

FIG. 3 is an enlarged vertical section view through the hopper in FIG. 1 and shows the picker and pin wheels unsectioned;

FIG. 4 is a largely schematic view, indicating the wire feeding and twisting chuck carriage and illustrating switching means associated therewith for controlling timed operations of the bristle feed controller;

FIG. 5 is a fragmentary perspective view of the invention in conjunction with a bristle transferring means in the forming of a picking wheel for receiving bristle clusters from the supply hopper and bringing them directly to insert position between the binding wires;

FIG. 6 is a front view of the mechanism shown in FIG. 5; and

FIG. 7 is a section along lines 7—7 of FIG. 6.

Only as much of the known machine as is necessary to understand the application of the invention thereto is here shown. To aid recognition of elements of the known machine, they are given the same reference numbers as in said patent.

Referring to FIGS. 1 to 3, a stock of bristles 124 is contained in the supply hopper 126 which slopes down to the picker wheel 80 fixed to shaft 120. This shaft can be oscillated but is here preferably rotated in one direction, so that the picker wheel moves unidirectionally across the hopper mouth. The picker wheel intrudes 40 into the hopper mouth along an arc of the wheel and is formed with a peripheral slot 143 which in traversing the hopper mouth collects a cluster 139 of bristles and carries the cluster toward a cluster conveying pin wheel 54. The pin wheel is formed with circular sides from the rims of which aligned pairs of pins 142 radiate, the arc 45 between each pair of aligned pins and the next pair comprising a cluster receiving and carrying space. Between its sides, the pin wheel has a groove 81 into which the picker wheel 80 intrudes in such manner that during movement of the picker slot 143 within the groove, it brings a cluster of bristles to the pin wheel arc between one aligned pair of pins 142 and the next. As the pin wheel rotates relative to the picker wheel, it extracts the bristle cluster from the picker slot and conveys the cluster to insert position between lower binding wire 10 and upper binding wire 38 which are being pulled past the insert position by a traveling chuck 24 (FIG. 4). The wires are suitably guided and spaced at the insert position to receive and carry away a cluster of bristles from the pin wheel 54. The pin wheel is fixed to a shaft 146. This shaft and the shaft 120 of the picker wheel 80 are driven from common drive means, such as suggested in said patent, in a ratio such that the pin wheel turns through a pin-to-pin arc during each revolution of the picker wheel 80. In each revolution of the picker wheel,

it collects a bristle cluster from the hopper 126 and brings it to an arc of the pin wheel. In successive revolutions of the picker wheel, therefore, successive pin-to-pin arcs or bristle conveying spaces of the pin wheel extract bristle clusters from the picker wheel and bring them successively to the insert position between the binding wires, and since the wires are moving, they carry the clusters away in lengthwise spaced positions. Curved plates 144 and 145 below the picker and pin wheels prevent clusters from dropping out of the wheels.

After a desired length of the binding wires has been fed by the chuck, its wire feeding stroke ends and its shaft 164 (FIG. 4) is rotated. The chuck rotation twists the wires together and locks the inserted bristle clusters between the twisted wire loops. The wires are then cut behind the twisted length and the chuck is opened to drop the completed work, consisting of a length of binding wires twisted about spaced bristle clusters, into a receiving space. Thereafter, a new brush forming routine begins and the chuck returns to grip the leading end of the wires in the machine and start a new wire feeding period.

As previously explained, the insertion of bristles between binding wires 10 and 38 is to stop a suitable time before the end of the wire feeding period and is not to resume until after the next wire feeding period occurs. Interrupting bristle insertion before the end of the wire feeding period leaves a bristle-free length of wires available, after the cutting operation, for grasping by the chuck at the start of the next wire feeding period. Bristle insertion between the wire feeding periods of successive brush forming cycles also must be interrupted.

According to the invention, bristle insertion is interrupted for the desired interval without stopping either the picker wheel 80 or pin wheel 54 but, instead, by interrupting the passage of bristles from hopper 126 into the picker slot 143. For this purpose, the invention provides bristle feed control means including a rocker 400 having a pair of arms 401 dependent from a hub 402 and straddling the picker wheel. The arms 401 are convexly curved on their rear edges substantially in the shape of an arc of the picker wheel and are of such length that when in rear position (full line position in FIG. 3), they effectively close the hopper mouth and shield the picker slot completely from reception of bristles. Slots 403 in the upper and lower walls of the hopper mouth enable the rocker arms 401 to move far enough back to insure the bristles being pushed back far enough to clear the locus of the picker wheel.

As long as the rocker arms stay in rear position, they prevent the feed of bristles from the hopper 126 into the picker slot 143. Thus, the picker wheel can continue its operation without taking in bristles and the pin wheel 54 can continue to rotate without receiving bristles from the picker wheel, so that a desired arcuate span of the pin wheel will be left empty and when this span traverses the insert position between the wires, no bristle clusters will be delivered to the wires. On the other hand, when the rocker arms 401 are in forward position (dotted line position in FIG. 3), they are sufficiently inward of the locus of the picker slot 143 not to interfere with free passage of bristles from the hopper 126 into the picker slot when this slot is traversing the hopper mouth. The picker wheel during its successive revolutions will then be effective to deliver successive bristle clusters to the pin wheel which will bring them one after another to the insert position between the wires. Screw stops 412a and 412b on ears 413, of arm 407, at opposite sides of a lug 414 of bracket 405, provide adjustable limits for the alternative positions of the rocker arms 401.

The invention provides means through which the bristle feed controller comprising rocker 400, with its arms 401, is set in one or the other of its alternative positions for desired times during each brush forming cycle. The hub 402 of the rocker is fixed to a shaft 404 journaled in a bracket 405 mounted to a frame plate 406. Extending

from shaft 404 is a crank arm 407 having pin-and-slot connection to a clevis 408 on the end of a plunger rod 409. The plunger rod is fixed to a plunger (not shown) inside an air cylinder 410 carried by the frame. Air for operating the plunger is valved to cylinder 410 through remote solenoid valves (not shown) similar to the valves provided for the several pneumatic actuators in the machine shown in said patent. The valve operating solenoid circuits for cylinder 410 can be timed from any suitable cyclic element of the machine. Preferably, the timing is controlled from the chuck carriage 162 indicated in FIG. 4.

The chuck carriage 162 is driven through a forward stroke (to the left in FIG. 4) to bring the chuck 24 into position for grasping the leading end of the binding wires and is driven through its return stroke to effect feed of the wires during a wire feeding period. After the carriage reaches its rear position at the end of the return stroke, its drive is interrupted and chuck 24 is rotated to twist the wires. The wires are then cut and the chuck opens to drop the completed work. A next forward stroke of the carriage can then be effected. Mounted on the carriage 162 is a two-way or transfer micro-switch 416 with operating buttons 416f and 416r at opposite ends. Assume the carriage is moving through its return stroke, to the right in FIG. 4, so that the chuck 24 is feeding the binding wires past the bristle insert position. Assume, also, that the rocker arms 401 (FIGS. 1 to 3) are in forward position, permitting feed of bristle clusters to picking wheel 80 and that the pin wheel 54 has been supplied with the clusters from the picking wheel and is inserting them at spaced intervals between the moving binding wires. Before the end of the return stroke of the carriage, hence before the end of the wire feeding period, a freely suspended arm 417 of the micro-switch assembly strikes a plunger 418 mounted in the frame and is moved clockwise (FIG. 4) to depress the switch button 416r. This trips the switch 416 to a position for closing the circuit of a solenoid valve (not shown) to valve air to cylinder 410 for actuating the plunger rod 409 forwardly, in a direction to move the rocker 400 from its forward position to its rear position, interrupting the feed of bristles from the hopper into the picker wheel 80. As a result, bristles will not be delivered to the pin wheel; leaving pin-to-pin arcs of the pin wheel empty. The timing of the action of switch 416 to cause bristle feed to be interrupted is such that the empty arcs of the pin wheel will start traversing bristle insert position for the binding wires before the end of the return stroke of the chuck carriage, so as to leave a terminal portion of the wires fed during the return stroke bare of bristles.

In a known manner, the switch button 416r is latched in depressed position and, hence, switch 416 remains in bristle-shut off control status until this button is released. After the switch button 416r has been depressed by the action of plunger 418 on the button-operating arm 417, the chuck carriage continues its return stroke. Plunger 418 is spring-loaded and permits the arm 417 to pass to the right during the completion of the carriage return stroke. During the forward stroke of the carriage, the arm 417 freely passes the plunger. At the end of the forward stroke of the carriage 162, the front switch button 416f strikes an adjustable frame-based element 420 and is depressed. Depression of the button 416f trips the switch 416 to alternative condition and releases the switch button 416r. The switch then remains in this alternative condition until the button 416r is again depressed during the carriage return stroke. In the alternative condition of the switch 416, it closes a solenoid valve circuit to valve air into cylinder 410 for operating the plunger rod 409 in a direction to set the rocker 400 in forward position. In this position, the rocker permits bristle feeding from the hopper 126 into the picker wheel 80. Hence, the picker wheel will supply bristle clusters to the pin wheel which will deliver them to the bind-

ing wires for an interval of the wire feeding period corresponding to the distance between the front and rear switch-operating elements 420 and 418.

FIGS. 5, 6 and 7 show the invention in relation to direct bristle transferring means between the hopper 126 and the binding wires 10 and 38. As shown, this transferring means comprises a picking wheel 80A fixed to a shaft 146A which corresponds to the shaft 146 of the pin wheel 54 (FIGS. 1 to 3). Picking wheel 80A has spaced sides 80L and 80R formed with peripheral teeth to provide alined interdental spaces or slots successively traversing the hopper mouth, each slot collecting a cluster 139 of bristles provided the hopper is not shut by the rocker arms 401. The wheel 80A carries the clusters contained in the interdental slots directly to the binding wires 10 and 38. Skipping of bristle insertion between the wires is effected without stopping rotation of the wheel 80A but by moving the rocker arms to their rear position and thus shutting off the feed of bristles to the wheel. The means for operating and timing the operation of the rocker 400 can be the same as previously described.

While the foregoing description sets forth the principles of the invention in connection with specific apparatus, it is to be understood that this description is made only by way of example and not as a limitation of the scope of the invention as set forth in the objects thereof and in the accompanying claims.

What is claimed is:

1. In a brush making machine operating through brush forming cycles to produce in each cycle a brush body with bristles bound between wires, a bristle supply hopper, means for transferring bristles from the hopper to the wires and including a rotary bristle picking member rotatably movable past the hopper mouth to pick up bristles for transfer to the wires, a feed control member movable between a feed-interrupting position across the hopper mouth to block passage of bristles from the hopper to the picking member and a feed-permitting position which allows passage of bristles from the hopper to the picking member, and means for periodically moving said feed control member between said feed-permitting and feed-interrupting positions in synchronism with said brush forming cycles to produce brush bodies having bristles bound between predetermined portions of said wires.

2. The invention according to claim 1, the bristles lying in the hopper across its width, the picking member being narrower than the hopper width and having a picking locus intermediate the hopper sides for picking the bristles by engagement therewith between their ends, and said feed control member including arms straddling the picking member to be operative in feed-interrupting position for engagement with the bristle portions at opposite sides of the picking locus.

3. The invention according to claim 2, the picking member being a wheel having an arc of intrusion into the hopper mouth and said arms having a curvature substantially conforming to the curvature of the wheel and being long enough to span the arc of intrusion of the wheel into the hopper mouth.

4. The invention as defined in claim 3, said feed control member being rockably mounted adjacent the hopper mouth for rockable movement of its arms across the bristle picking locus of the picking wheel during the shifting of the feed control member between its alternative positions.

5. The invention according to claim 4, the picking wheel being peripherally provided with a picker slot to collect a cluster of bristles from the hopper during traverse across the hopper mouth, and said arms in their feed-interrupting position blanking said slot to prevent ingress of bristles therein.

6. The invention according to claim 5, the picking wheel being unidirectionally rotated and disposed between the hopper mouth and the binding wires for transferring

bristles directly from the hopper to the binding wires, the wheel being provided with a plurality of said picker slots around its periphery to collect bristle clusters successively and deliver them one after another to the binding wires during rotation of the wheel, said arms in their feed-interrupting position blanking out a plurality of the picker slots traversing the hopper mouth.

7. The invention as in claim 5, there being a single picker slot in the picking wheel, the transferring means also including a conveyor wheel between the picking wheel and the binding wires and provided peripherally with equidistant bristle cluster conveying arcs for successively receiving clusters from the picker slot during successive revolutions of the picking wheel and delivering the clusters to the binding wires, a number of successive conveying arcs being left empty in accordance with the number of revolutions performed by the picking wheel while the picker slot is being blanked by said arms.

8. In a brush making machine such as defined in claim 1, cyclically functioning means for alternating the feed control member between its feed-permitting and feed-interrupting positions in accordance with required intervals of bristle transfer and interruption of transfer to the binding wires during each brush forming cycle.

9. In a machine such as defined in claim 8, the cyclically functioning means including an actuator for said feed control member and means synchronized with stages of the brush forming cycle for timing the actuator operation.

10. In a machine such as defined in claim 9, wherein the binding wires are fed past the transferring means to receive bristles therefrom in lengthwise spaced positions between the wires, said timing means including wire feeding mechanism.

11. In a machine such as defined in claim 10, the wire feeding means comprising a chuck for gripping the wires and a reciprocative carriage mounting the chuck, said actuator for the feed-interrupting and feed-permitting member being electrically controlled through switch means, the timing means including said switch means responsive to the positions of the carriage.

12. In a brush making machine, a supply hopper for brush bristles, a bristle picking wheel continuously rotating across the hopper mouth and peripherally recessed parallel to its axis of rotation for gathering the bristles in clusters from the hopper during revolutions past the hopper, and bristle feed control means including a movably mounted member having alternative positions in one of which it permits passage of bristles from the hopper to the picking wheel and in the other of which it shields the picking wheel from reception of bristles through the hopper mouth during continued rotation of the wheel.

13. In a brush making machine operating through brush forming cycles to produce in each cycle a brush body with bristles bound between wires, a supply hopper for brush bristles, a bristle picking wheel having a bristle picking locus of movement across the hopper mouth to take the bristles from the hopper, and means for controlling the passage of bristles from the hopper to the picking wheel including a member mounted adjacent the hopper mouth and provided with a pair of elements straddling the picking wheel and movable across the bristle picking locus from a position inward of the locus and permitting passage of bristles from the hopper to the

60 picking wheel into an alternative position across the hopper mouth for shielding the picking wheel from reception of bristles, and means for operating said device to shift said pair of elements from one position to the other in synchronism with said brush forming cycles to produce brush bodies having bristles bound between predetermined portions of said wires.

14. In a brush making machine operating through brush forming cycles to produce brush bodies having bristles bound between predetermined portions of said wires, a supply hopper for brush bristles, a bristle picking

wheel continuously rotating across the hopper mouth and peripherally recessed parallel to its axis of rotation for gathering the bristles in clusters from the hopper during revolutions past the hopper, bristle feed control means including a movably mounted member having alternative positions in one of which it permits passage of bristles from the hopper to the picking wheel and in the other of which it shields the picking wheel from reception of bristles through the hopper mouth during continued rotation of the wheel, and means for periodically moving said feed control member between said alternative positions

thereof in synchronism with said brush forming cycles to produce brush bodies having bristles bound between predetermined portions of said wires.
